DRAFT RIGGING

Emil H. Blattner, Williamsville, N.Y., assignor to The Symington-Gould Corporation, Depew, N.Y., a corporation of Maryland

Application March 8, 1956, Serial No. 570,334

6 Claims. (Cl. 213—60)

This invention relates to draft rigging for railway vehicles and has for its primary object the provision of improved draft rigging for application to a vehicle having fixed center sills whereby an associated coupler, without interfering with its normal operation, is permitted travel in buff on the order of that obtainable with floating center sills.

To afford better cushioning for protecting lading equipped with fixed center sills under humping and other conditions met in service, it has been proposed to increase the length of the A.A.R. standard draft gear pocket between the center sills to accommodate draft gears of longer travel and correspondingly greater capacity. However, while such larger draft gears are of advantage in decreasing lading damage, the maximum travel so obtainable is limited to the permissive travel between the horn of the associated coupler and the fixed striker at the adjacent end of the center sills.

It is, therefore, an object of the present invention to provide an improved draft rigging for fixed center sills wherein the striker is adapted for movement in buff with the coupler over a part of the latter's travel, whereby the travel of the coupler in buff may be increased to the extent desired amply to cushion buffing forces.

Another object of the invention is to provide improved draft rigging wherein by associating the striker for limited movement with the coupler and cushioning buffing forces by a plurality of cushioning mechanisms, at least one of which is pocketed inwardly of the center filler, cushioning capacity in excess of any now contemplated is obtainable without resort to relatively expensive floating center sills.

Other objects and advantages of the invention will appear hereinafter in the detailed description, be particularly pointed out in the appended claims and be illustrated in the accompanying drawings, in which:

Figure 1 is a plan view of a proposed embodiment of the draft rigging of the present invention shown applied to the center sills of the railway vehicle with portions broken away and shown in section to more clearly illustrate certain of the details of construction;

Figure 2 is a side elevational view of the draft rigging of Figure 1 with portions broken away and shown in section to more clearly illustrate certain of the details of construction;

Figure 3 is a fragmentary horizontal sectional view on an enlarged scale of the outer end portion of the draft rigging taken along the lines 3—3 of Figure 2;

Figure 4 is a vertical sectional view on the scale of and of the portions shown in Figure 3, the view being taken along the lines 4—4 of Figure 1;

Figure 5 is a vertical sectional view taken along the lines 5—5 of Figure 3; and

Figure 6 is a vertical sectional view taken along the lines 6—6 of Figure 3.

Referring now in detail to the drawings in which like reference characters designate like parts, the improved draft rigging of the present invention is intended to be

2

applied to a railway vehicle (not shown) having as part of its underframe fixed center sills 1, those illustrated being of the conventional Z-shape and bounding a channel 2 of rectangular cross-section and open at the bottom which extends from end to end of the vehicle. Although adapted as well for application to rigid shank and other types of couplers, the draft rigging has been illustrated in association with a universally angling coupler 3 of the type recently made an alternate standard and known as the A.A.R. Type "F."

As is usual with Type "F" couplers, the coupler 3 is pivotally connected for universal angling to a vertical yoke 4 by a connecting pin 5 and the shank 6 of the coupler and is supported by a resilient coupler carrier 7 pocketed in a striking casting 8 mounted at one end of the channel 2 between the center sills 1. The conventional associated striking casting is fixed to the center sills. However, the striking casting 8 of the draft rigging of the present invention is designed to be slidably mounted in the center sills and movable or slidable longitudinally relative thereto. For this purpose, its outer end, housing the pocket 9 in which the resilient coupler carrier 7 is pocketed, is slidably supported on a supporting or rest plate 10 which in turn is connected at either end to and supported by a pair of cheek plates 11, one fixed to the outside of the longitudinally extending vertical wall 12 of each of the center sills 1.

In lieu of the usual integral draft lugs the striking casting 8 has as its rearward portion a pair of transversely spaced arms or extensions 13 having aligned key slots 14 extending transversely therethrough for the reception of a draft key 15. Inwardly of the coupler and straddled by the arms 13 is a follower block 16, which in the illustrated embodiment has its front face 30 contoured to accommodate the convex spherically and cylindrically surfaced butt 18 of the coupler 3. The follower block 16 also has a transversely extending key slot 19 for the reception of the draft key 15 but its slot is lengthened forwardly with respect to the slots 14 in the arms 13 so as to permit motion rearwardly of the follower block 16, coupler 3 and yoke 4 relative to the striking casting 8. Beyond the arms 13, the draft key 15 slides in transversely aligned key slots 20, one in the vertical wall 12 of each of the center sills 1, this second pair of slots being lengthened rearwardly with respect to the other slots to permit rearward motion relative to the center sills, not only of the coupler and related components connected thereto, but of the striking casting 8, as well. Desirably, the slots 20 in the center sills are reinforced by portions of the cheek plates 11.

Contained within the yoke 4 between its rear wall 21 which connects its longitudinally extending arms 22 and the follower block 16, is a front cushioning mechanism 23 of suitable type, that shown being a housed draft gear of the type now widely used in the present standard draft gear pocket and having a plunger 24 projecting from its forward end and engaging the rear end of the follower block 16. Interposed between the cushioning mechanism 23 and the rear wall 21 of the yoke 4 is a rear follower 25 which projects in the usual manner laterally or transversely beyond either sides of the yoke and in the conventional draft rigging would be adapted to engage rear stop lugs fixed to the center sills. However, since this would limit the travel in buff to that of a draft gear accommodatable within the yoke 4 and the main objective of the present invention is to afford travel on the order of that obtainable with a cushion underframe, the rear follower 25, instead, is adapted to engage and react against a pair of rigid buffing columns 26, one at either side of the yoke, and each sliding in one of a pair of passages 27 of corresponding

cross section in and extending longitudinally through a center filler 28 on opposite sides of the king post 29.

The purpose of the buffing columns 26 is to transmit buffing forces from the front cushioning mechanism 23 past the center filler 28 to a second or rear cushioning mechanism 30 seated in the center sills 1 between the center filler and a backstop 31 fixed to the center sills. Since not limited in longitudinal dimension by the restricted space available forwardly of the center filler, the rear cushioning mechanism can be of any length and type suitable to afford travel and capacity sufficient, when added to that of the front cushioning mechanism, to meet any possible demands for cushioning in buff. The type illustrated is a housed double-ended draft gear, such, for example, as shown in my copending application Serial No. 546,033, filed on November 10, 1955, with a plunger 32 at either end, each having substantially the same travel as that of the front cushioning unit. The illustrated arrangement thus provides a total travel in buff about triple that of a conventional draft gear and with a corresponding increase in capacity.

Buffing forces may be transmitted to the rear cushioning mechanism and therefrom to the backstop 31 through front and rear followers 33, one between the buffing columns and the front of the plungers 32 and the other between the rear of the plungers and the backstop. Straddling the rear wall 21 of the yoke 4, the buffing columns 26 preferably have outstanding flanges 34 adjacent the forward ends, both to increase their bearing area with the rear follower 25 of the front cushioning mechanism 23 and to hold to a minimum the lateral play permitted the columns and the rear end of the yoke. It will be noted that the rear cushioning mechanism 30 and its followers 33, as well as the yoke 4, once installed, are held in assembled position by cross ties 37 fixed as by riveting to the center sills 1 across the underside of the channel 2 and that the same function is performed for the connecting pin 5 by a cross web 38 integral with the striking casting 8.

Depending upon the operating characteristics desired, the rear cushion 30 may either be relatively stiff so as to cushion only under severe buffing forces, or soft acting so as to afford with the front cushioning mechanism 23 a relatively soft cushion under normal buffing forces. In either case, the tandem-arranged front and rear cushions, at least under excessive buffing forces, will act in series to cushion the forces. The maximum force in draft being much less than that in buff and adequately cushioned by the front cushioning mechanism alone, the draft rigging of this invention is designed for selective travel and has no pulling connection between the rear cushioning mechanism and the coupler so that only the front cushioning mechanism acts in draft.

It has been mentioned that the pair of key slots 20 are lengthened rearwardly while the slot 19 in the front follower block 16 is lengthened forwardly, both relative to the pair of slots 14 in the striking casting 8 between which and the draft key 15 there is substantially no longitudinal play. With the three slots so lengthened, the draft key 15 in the normal or at rest position of the draft rigging, is held tight against the front end of the center sill slots and the rear end of the slot in the follower block. Consequently, while in draft, the front follower block 16 is held by the draft key 15 against forward motion and serves as a draft stop for the front cushioning mechanism, it is enabled to move rearwardly, first relative to both center sills and striking casting to the extent of the forward lengthening of its slot 19 and then with the striking casting relative to the center sills to the extent of the rearward lengthening of the center sill slots 20. By adjusting these lost motions so that they in sum equal the total travel of the cushioning mechanisms and that between the front follower and the striking casting is restricted relative to the normal spacing between the coupler horn 36 and striker 35 of the striking

casting so that the minimum clearance between the horn and striker will be sufficient to permit the desired angling of the coupler relative to the striking casting, full benefit is derived from the long travel afforded by the draft rigging and the coupler is enabled to function normally throughout such travel.

From the above detailed description, it will be apparent that there has been provided an improved draft rigging for application to railway vehicles having fixed draft sills which, in conjunction with capacity more than adequate to cushion any buff forces now envisioned under service conditions, affords travel in buff on the order of that obtainable with cushioned underframes, both without interference with normal functioning of the coupler. It should be understood that the described and disclosed embodiment is merely exemplary of the invention and that all modifications are intended to be included which do not depart from either the spirit of the invention or the scope of the appended claims.

20 I claim:

1. In railway draft rigging, the combination with center sills, a center filler fixed to said sills, a coupler and a yoke connected thereto, of a striker slidable longitudinally of said fixed sills, front and rear cushioning mechanisms 25 arranged in tandem in said sills respectively within said yoke and rearwardly of said center filler, rigid means slidable in and extending through said center filler for transmitting buffing forces between said cushioning mechanisms, and lost motion means connecting said striker to said coupler and said striker and coupler to said center sills, said means permitting said coupler to travel rearwardly in buff relative to said sills for substantially the total travel of said cushioning mechanisms and causing said striker to move rearwardly with said coupler over a part of said travel.

2. In railway draft rigging, the combination with fixed center sills, a center filler fixed to said sills, a coupler and a yoke connected thereto, of a striking casting in and slidable longitudinally of said center sills, front and rear cushioning mechanisms in said sills, one within said yoke and the other rearwardly of said center filler, rigid means extending through said center filler for transmitting buffing forces from said front to said rear mechanism, and lost motion means restraining movement of said striking casting forwardly relative to said sills and causing limited movement of said striking casting with said coupler during movement of said coupler rearwardly relative to said sills under buffing forces.

3. In railway draft rigging, the combination with fixed center sills, a coupler and a yoke pivotally connected thereto, of striker means in and slidable longitudinally of said sills, a front follower block within said yoke, and key and slot means connecting said striker means, follower block and sills and restraining forward movement of said striker means and follower block, relative to said sills, said key and slot means permitting said follower block and therethrough said coupler and yoke to travel rearwardly under buffing forces and causing said striker means to move rearwardly with said follower block over a part of said travel.

4. In railway draft rigging, the combination with fixed center sills, a coupler and a yoke connected thereto, of striker means slidable longitudinally of said sills, and lost motion means connecting said striker means to said coupler and said sills said lost motion means permitting limited rearward movement of said coupler relative to said striker means and thereafter maintaining clearance between a horn of said coupler and said striker means by causing said striker means to move with said coupler during further movement thereof rearwardly relative to said sills.

5. In railway draft rigging, the combination with fixed center sills, a center filler fixed to said sills, a coupler and a yoke pivotally connected thereto, of a striker in and slidable longitudinally of said sills, front and rear

cushioning mechanisms arranged in tandem in said sills, one within said yoke and the other rearwardly of said center filler, rigid means slidable in and extending through said center filler for transmitting buffing forces between said cushioning mechanisms, a front follower block within said yoke between said front cushioning mechanism and said coupler, and key and slot means connecting said striker and follower block and restraining forward movement thereof relative to said sills, said key and slot means permitting rearward travel of said follower block and therethrough said coupler and yoke relative to said sills for substantially the total travel of said cushioning mechanisms and causing said striker to move rearwardly with said coupler over a part of said travel.

6. In railway draft rigging, the combination with fixed 15 center sills, a center filler fixed to said sills, a coupler and a yoke pivotally connected thereto, of a striker in and slidably longitudinally of said sills, said striker having an outer end pocketing a resilient coupler carrier and slidably supported on means carried by said sills, 20

front and rear cushioning mechanisms arranged in tandem in said sills, one within said yoke and the other rearwardly of said center filler, rigid means slidable in and extending through said center filler for transmitting buffing forces between said cushioning mechanisms, a front follower block within said yoke between said front cushioning mechanism and said coupler, and key and slot means connecting said striker and follower block and restraining forward movement thereof relative to said sills, said key and slot means permitting rearward travel of said follower block and therethrough said coupler and yoke relative to said sills for substantially the total travel of said cushioning mechanisms and causing said striker to move rearwardly with said coupler over a part of said travel.
